UNITED STATES PATENT OFFICE.

HERMANN PICHLER, OF URACH, WÜRTEMBERG, GERMANY.

DESIGN FOR A TABLE-COVER.

SPECIFICATION forming part of Design No. 11,866, dated July 13, 1880.

Application filed April 17, 1880. Term of patent 7 years.

To all whom it may concern:

Be it known that I, HERMANN PICHLER, of Urach, Württemberg, in the Empire of Germany, have invented a new and original Design for Table-Covers, of which the following is a specification.

My invention relates to a new design for table-covers, napkins, and other similar articles; and it consists in the new ornamentation and configuration of parts hereinafter specifically pointed out and described.

The accompanying photograph illustrates my new design.

In the center of the fabric, on the background, is the representation of a circle, A, ornamented with a wreath, a, and at equal intervals medallions of lions' heads, b, facing outward. In the mouths of the lions are scarfs, from which depend Maltese or iron crosses. Inside the ring or circle is an ornamental border, B, from which rise at regular intervals vases d, directly opposite the medallions. Two opposite vases contain the symbols of the arts and sciences, while the other two contain fruits and flowers. Between the vases are representations of winged angels e, holding palm-leaves in their outstretched hands.

The above-mentioned central figure is inclosed in a rectangular border, C, ornamented with stars, in the angles of which are repre-

sentations E of eagles, each eagle bearing a shield on its breast, and each embraced by olive and oak branches. Outside of the border C is another border, D, with semicircular arches, in which are bunches f, composed of 35 wheat-heads and the blossoms of the cockle or corn rose.

I claim—

1. The design for a table-cover, consisting of the central ring, A, medallions b, border B, 40 vases d, and figures e, substantially as shown.
2. The design for a table-cover, consisting of the ring or circle A, medallions b, border B, vases d, figures e, border C, and the figures E, substantially as shown 45
3. The design for a table-cover, consisting of the border D and bunches f of wheat-heads and blossoms of the cockle or corn rose, substantially as shown.
4. The design for a table-cover, consisting 50 of the central ring or circle, A, medallions b, border B, vases d, figures e, border C, representations of eagles, &c., in the angles, border D, and bunches of wheat-heads and corn-rose blossoms f, substantially as shown.

HERMANN PICHLER.
